FLUORESCENT TUBE LIGHTING FIXTURE

Robert M. Garth, Jacksonville, Fla., assignor to
H. C. Biglin Company, Incorporated

Application April 23, 1949, Serial No. 89,239

4 Claims. (Cl. 240—51.11)

1

This invention relates generally to lighting fixtures, and more particularly to lighting fixtures in which the illuminant is of the fluorescent tube type.

An object of my invention is to provide a fluorescent tube lighting fixture having a completely free and open top for relamping from above.

Another object of my invention is to provide a fluorescent tube lighting fixture comprising a rigid unit without hinges or parts requiring removal or moving during relamping of the fixture.

Another object of my invention is to provide a fluorescent tube lighting fixture in which the ballast or transformers for use therewith are housed within the side frame structure.

Another object of my invention is to provide a fluorescent tube lighting fixture in which side light and glare is eliminated.

Another object of my invention is to provide a fluorescent tube lighting fixture which is simple in construction, pleasing in design, inexpensive to manufacture and efficient in operation.

Other and further objects and advantages will be apparent from the following description taken in connection with the accompanying drawings in which like characters of reference designate corresponding parts throughout the several views, and wherein:

Fig. 1 is a top plan view of a lighting fixture embodying my invention.

Fig. 2 is a side view of the lighting fixture shown in Fig. 1, with supporting rods removed.

Fig. 3 is a bottom plan view of the lighting fixture shown in Fig. 1.

Fig. 4 is an enlarged cross-sectional view taken along the line 4—4 in Fig. 1.

Fig. 5 is an end view of the lighting fixture shown in Fig. 1.

Fig. 6 is an enlarged cross-sectional view taken along the line 6—6 in Fig. 1.

In the embodiment chosen for illustration, the lighting fixture is provided with a rectangular frame having side members 10, 10' and end members 11, 11'.

Each of the side frame members 10, 10' has an inner side wall 12 and an outer side wall 13 joined together at the top and bottom so as to form a closed side chamber 14 within which are mounted the ballast or transformers 15. By placing the ballast in the sides of the fixture frame, the necessity for a box on the ceiling for enclosing the ballast is eliminated. The inner wall of each side frame member presents a smooth, perpendicular surface facing the inner wall of the opposite side frame member.

Each of the end frame members 11, 11' has an 55 that many modifications and changes can be

2

inner end wall 16 and an outer end wall 17 joined together at the top and bottom so as to form a closed end chamber 18. The inner wall of each end frame member presents a smooth, perpendicular surface facing the inner wall of the opposite end frame member. Tube holders 19, of well known construction, are secured to each inner end wall 16 so as to face the corresponding holder on the opposite end and the holders 19 are arranged so that the fluorescent tubes 20 can be slipped into the holders from the top of the fixture. The fixture according to my invention presents an entirely unobstructed top for relamping from above. There are no hinges and no parts to be moved or removed in order to gain access to the tubes and starters in my lighting fixture. No part of my fixture projects above any tube or starter therein. No part of my fixture within the rectangle defined by the inner side walls 20 and inner end walls extends above the fluorescent tubes in my fixture.

Sockets 21 are mounted in each end chamber 18 for the reception of starters 22 for use with the fluorescent tubes 20, as is well known. The starters 22 are placed in position in the sockets 21 by insertion through holes 23 in the top of the end chamber 18. When in position in the sockets 21, the starters project through the holes 23 and can be removed from the top of the fixture by simply withdrawing them by hand, and no part of the fixture has to be moved or removed to accomplish the positioning or removal of any starter in my fixture.

Also mounted on each end frame member is a supporting rod or tube 24, 24' by means of which the fixture is supported from a ceiling or other overhead structure (not shown). A switch 25, of customary construction, is mounted on the inner wall of one end frame member in a position below the tube sockets 19 so as not to obstruct the removal of any of the tubes from the top of the fixture.

As best seen in Fig. 2, no part of my fixture, between the end frame members, extends either above or below the side frame members. Longitudinal and cross-frame louvers 26 and 27, respectively, are placed within the rectangular frame below the tubes 20, and they are spaced so as to form 2-inch square openings through which light from the tubes 20 passes downwardly from the fixture. This arrangement eliminates side light and glare, and results in a fixture which is both efficient and pleasing to the eye.

It will be obvious to those skilled in the art that many modifications and changes can be

made in the structure shown without departing from the scope of my invention as defined in the appended claims.

Having thus described my invention, what I claim and desire to secure by Letters Patent is:

1. In a fluorescent tube lighting fixture, a substantially rectangular frame having side frame members and end frame members, said side frame members having an inner side wall and an outer side wall arranged to form side chambers, said end frame members having an inner side wall and an outer side wall arranged to form end chambers, supports for said fixture secured to said end frame members, fluorescent tube holders mounted on said inner side walls of said end frame members and arranged for the relamping of said fixture from the top, fluorescent tubes mounted in said tube holders, starters for said tubes mounted on said end frame members, transformers for said tubes mounted in said side frame members, and longitudinal louvers and cross-frame louvers mounted in said rectangular frame beneath said fluorescent tubes to form openings through which light from said tubes passes downwardly from said fixture, each said inner side wall presenting an unobstructed surface, all parts of said fixture between said end frame members being confined between the planes containing the top and bottom respectively of said side frame members and arranged to provide an entirely clear open space above said tubes.

2. In a fluorescent tube lighting fixture, a substantially rectangular frame having side frame members and end frame members, said side frame members having an inner side wall and an outer side wall arranged to form side chambers, said end frame members having an inner side wall and an outer side wall arranged to form end chambers, supports for said fixture secured to said end frame members, fluorescent tube holders mounted on said inner side walls of said end frame members and arranged for the relamping of said fixture from the top, fluorescent tubes mounted in said tube holders, starters for said tubes mounted in the top of said end frame members, transformers for said tubes mounted in said side frame members, and longitudinal louvers and cross-frame louvers mounted in said rectangular frame beneath said fluorescent tubes to form openings through which light from said tubes passes downwardly from said fixture, each said inner side wall presenting an unobstructed surface, all parts of said fixture between said end frame members being confined between the planes containing the top and bottom respectively of said side frame members and arranged to provide an entirely clear open space above said tubes.

3. In a fluorescent tube lighting fixture, a substantially rectangular frame having side frame members and end frame members, said side frame members having an inner side wall and an outer side wall arranged to form side chambers, said end frame members having an inner side wall and an outer side wall arranged

to form end chambers, supports for said fixture secured to said end frame members, fluorescent tube holders mounted on said inner side walls of said end frame members and arranged for the relamping of said fixture from the top, fluorescent tubes mounted in said tube holders, starters for said tubes mounted in the top of said end frame members, transformers for said tubes mounted in said side frame members, and longitudinal louvers and cross-frame louvers mounted in said rectangular frame beneath said fluorescent tubes and spaced apart so as to form openings approximately two inches square through which light from said tubes passes downwardly from said fixture, each said inner side wall presenting a smooth, unobstructed substantially perpendicular surface, all parts of said fixture between said end frame members being confined between the planes containing the top and bottom respectively of said side frame members and arranged to provide an entirely clear open space above said tubes.

4. In a fluorescent tube lighting fixture, a substantially rectangular frame having side frame members and end frame members, said side frame members having an inner side wall and an outer side wall arranged to form closed side chambers, said end frame members having an inner side wall and an outer side wall arranged to form closed end chambers, supports for said fixture secured to said end frame members, fluorescent tube holders mounted on said inner side walls of said end frame members and arranged for the relamping of said fixture from the top, a fluorescent tube mounted in each pair of said tube holders, starters for said tubes mounted in the top of said end frame members, transformers for said tubes mounted in said side frame members, and longitudinal louvers and cross-frame louvers mounted in said rectangular frame beneath said fluorescent tubes and spaced apart so as to form openings approximately two inches square through which light from said tubes passes downwardly from said fixture, each said inner side wall presenting a smooth, unobstructed substantially perpendicular surface, all parts of said fixture between said end frame members being confined between the planes containing the top and bottom respectively of said side frame members and arranged to provide an entirely clear open space above said tubes.
